US0D1032722S

(12) **United States Design Patent** (10) Patent No.: **US D1,032,722 S**
(45) Date of Patent: ** Jun. 25, 2024

(54) **GAMING MACHINE**

(71) Applicant: **AGS LLC**, Las Vegas, NV (US)

(72) Inventors: **Karl Frederick Zedell, Jr.**, Johns Creek, GA (US); **Benjamin Martin**, San Francisco, CA (US); **Carlos Martin Terminel Iberri**, San Jose, CA (US); **Daniel Kendall Harden**, Carmel-by-the-Sea, CA (US); **Zack Stephanick**, San Francisco, CA (US); **James Ely Tillery**, Tucker, GA (US); **Kevin Hohman**, North Las Vegas, NV (US); **Parry Staley**, Decatur, GA (US); **Matthew Rodgers**, Cumming, GA (US)

(73) Assignee: **AGS LLC**, Las Vegas, NV (US)

(**) Term: **15 Years**

(21) Appl. No.: **29/835,491**

(22) Filed: **Apr. 19, 2022**

(51) LOC (14) Cl. **21-03**

(52) U.S. Cl.

USPC **D21/369**
